CATHODE RAY TELEVISION TUBE

John S. Vansant, Huntingdon Valley, Pa., assignor to Philco Radio and Television Corporation, Philadelphia, Pa., a corporation of Delaware

Application March 30, 1942, Serial No. 436,875

5 Claims. (Cl. 250—164)

This application relates to cathode ray tubes and more particularly to cathode ray tubes employed in television receivers.

In the cathode ray tubes which have been used in television receivers up to the present time, it has been the practice to cover the entire face of the tube with fluorescent material and to employ some form of mask externally of the tube to cover that portion of the tube on which the picture does not appear. It has also been necessary to mask the edges of the picture itself since normally the edges are ragged in appearance and tend to detract from the artistic value of the picture.

The use of an external mask may have any of several detrimental effects depending on the amount of picture masked out and the angle from which the picture is viewed. Since it is impossible to accurately cover the part of the tube on which the picture does not appear, the mask reduces to some extent the size of the picture which may be seen. Furthermore, if the picture is viewed from an angle the effect of parallax enters in because the fluorescent screen is on the inside surface of the thick glass face of the tube. When the screen is viewed from one side the mask covers a portion of the picture on that side and allows the ragged edge of the picture to show on the other. Masks also have the highly objectionable effect of picking up light from the cathode ray tube screen and from the room, thereby causing a bright border around the picture which detracts greatly from the contrast of the picture. Moreover, light which is reflected from the mask and back to the screen further reduces this contrast.

The primary object of this invention is to devise a television picture tube which requires no mask to delineate the visible picture area, and which, notwithstanding the absence of a mask, is characterized in that the outline of the reconstructed picture is sharply defined.

Other objects of the invention will be apparent to those skilled in the art from the following description and accompanying drawing, in which

Fig. 1 is a side elevational view of a cathode ray tube constructed according to the invention, with a portion broken away to show the fluorescent screen;

Fig. 2 is a face view of the end of the tube;

Fig. 3 is a side elevational view of the tube parts during the construction of the tube; and

Fig. 4 is a face view of the mask employed according to the invention.

Referring first to Figs. 1 and 2, there is shown

a cathode ray tube 1 having a circular transparent glass face 2 on which there is a fluorescent screen 3 of rectangular shape. In the operation of the tube, the rectangular screen 3 is excited to luminescence by an electron stream projected from an electron gun within the tube and deflected by suitable deflecting means (not shown), as will be well understood. In the illustration the screen 3 is shown as having a rectangular shape but it is to be understood that the screen may be made to have any desired shape in accordance with the invention.

The method of applying the rectangular screen 3 to the tube, according to the invention, will now be described. The tube envelope may be formed of two parts 4 and 5 which are shown in Fig. 3 prior to their being joined along the dotted line 6 of Fig. 1. The screen is formed on the face of part 5, prior to the joining of the parts, as follows. The inside of part 5 is first completely cleaned to make it chemically free from any foreign matter. Following this, a mask 7, e. g. of paper, celluloid, or other material, such as shown in Fig. 4, is dropped into part 5 so as to fit over the inner surface of the face 2. The mask is preformed so that it conforms in size and shape with the size and shape of face 2, and an opening is formed therein corresponding to the size and shape of the screen desired. This mask should be made of a material which is chemically inert, e. g. chemical filter paper or other material which will leave no residual deleterious matter. The material used for the mask, in addition to being chemically inert, may desirably have physical characteristics which permit it to be easily rolled or bent, and which permit it to adhere snugly to the glass face at every point of contact. The mask should preferably be not deformable in its own plane, however, for any deformation may result in the shape of the screen being distorted. The mask may be rolled up for insertion in the part 5 in the case of the conical form shown, or it may be dropped in flat in any case where the shape of part 5 permits, it being understood that the tube may take any desired form. A small amount of distilled water may then be introduced and allowed to wet the mask so as to cause it to adhere to the surface of the glass, as shown in Fig. 3. The excess water is then poured out, and an air jet may be used to dry the inside of part 5 and the mask until the glass is dry but the mask is still sufficiently wet to adhere to face 2. The tube is then ready for the application of the fluorescent screen.

The first step in the application of the screen is to apply a binding material uniformly over the exposed inner face surface. Any suitable binding material may be employed, for example a dilute solution of sodium silicate (commercial water glass) or potassium silicate may be used. The binding material may be allowed to overlap the mask without deleterious effect. After the binding material has been applied, the fluorescent material, e. g. zinc sulphide or any of the other materials well known in the cathode ray tube art, is applied in known manner on the binder, for example by the "air settling" method. The tube may then be placed face uppermost and the inner surface of the face dried with a jet of air. When the inside of the tube has completely dried no further adhesion between the mask and the face of the tube will be effected, and the mask will generally drop by the force of gravity alone, carrying with it the unwanted fluorescent material and leaving a fluorescent screen as shown in Figs. 1 and 2 having sharply defined edges surrounded by the uncoated glass face. The tube parts are then assembled.

In the operation of the cathode ray tube provided by the invention, the electron beam is preferably swept somewhat beyond the four edges of the fluorescent screen, but since the border around the screen is transparent glass the observer sees no picture beyond the edge of the screen. The tube as shown has the further advantage that the surfaces in back of the tube face are painted with a dull black graphite mixture (aquadag) so that there is no light visible within the tube, and hence the contrast is very great.

The drawing illustrates the use of a rectangular screen that is particularly advantageous for television program reception. Other purposes may require different shapes of the screen and it is to be understood that the invention is not intended to be limited to a rectangular screen inscribed in a circular tube, but is intended to cover any form of screen in round, rectangular, or other shaped tube faces. Various modifica-

tions of the preferred screen application method described above may be used without departing from the scope of the invention.

I claim:

5 1. A cathode ray tube having a transparent face, a fluorescent screen extending over a predetermined portion only of said face, said screen corresponding in shape to the shape of the picture to be shown, the area of said screen being slightly less than the area to be scanned by the cathode ray, the portion of said face surrounding said screen being fully transparent to visible light.

10 2. A cathode ray tube as claimed in claim 1, characterized in that the visible surfaces of the tube in back of the tube face are painted a dull black, whereby to augment the contrast between the fluorescent screen portion and the transparent portion surrounding said screen.

15 3. In a picture reconstituting device, a cathode ray tube having a transparent face, a fluorescent coating extending over a predetermined central portion only of said face, the area of said portion being somewhat less than the area scanned by the cathode ray, all of said viewing screen, and at least a portion of the surrounding uncoated face, being transparent and visible to an observer.

20 4. In a cathode ray tube having a circular glass face at one end, a rectangular fluorescent screen extending over a predetermined portion only of said face and corresponding with the shape of the picture to be shown, the remainder of said face being uncoated and transparent.

25 5. A cathode ray picture tube having a visible screen supporting surface, a fluorescent screen extending over a portion only of said visible surface, said screen corresponding in shape to the picture to be produced thereon, the area of said screen being slightly less than the area to be scanned by the cathode ray, the portion of said surface surrounding said screen being unmasked.

JOHN S. VANSANT.
